UNITED STATES PATENT OFFICE.

ROBERT C. HOPKINS, OF ALLIANCE, OHIO.

PICKLING-TANK CONSTRUCTION.

Application filed June 10, 1924. Serial No. 719,121.

To all whom it may concern:

Be it known that I, ROBERT C. HOPKINS, a citizen of the United States, residing at Alliance, in the county of Stark and State 5 of Ohio, have invented certain new and useful Improvements in Pickling-Tank Constructions, of which the following is a specification.

The invention relates to improvements in acid tanks and more particularly to a tank adapted to contain sulphuric or hydro-chloric acid for pickling metal sheets and bars.

Tanks of this character are usually made 15 of heavy wood timbers secured together by bolting or the like, and difficulty is experienced in making tightly sealed ends, and also in the breaking or destruction of the end walls by the endwise ramming of bars, 20 sheets and the like being pickled in the tank.

The objects of the invention are to provide a tank of this character in which the side and bottom walls are formed of wood and the end walls of acid resisting metal; 25 each end wall being provided with flanges to which the wooden side and bottom walls of the tank are bolted or otherwise connected, these flanges being split or slotted at their corners to permit expansion and 30 contraction of the metal end plates, a rib being formed upon each flange for engagement with corresponding grooves in the wooden side and bottom walls; a wooden wedge being provided at each corner of the 35 end wall to prevent leaking.

The above and other objects may be attained by constructing the tank in the manner illustrated in the accompanying drawings, in which—

40 Figure 1 is an end view of an acid tank embodying the invention, a portion of one corner of the timbers being broken away;

Fig. 2, a section on the line 2—2, Fig. 1;

45 Fig. 3, an enlarged, sectional view of one corner of the tank;

Fig. 4, a section on the line 4—4, Fig. 1; and

Fig. 5, a detached perspective view of one of the metal end walls.

50 Similar numerals refer to similar parts throughout the drawings.

Each end wall is indicated generally at 1 and is formed of a single plate of acid resisting metal, such as a copper-tin-lead-nickle 55 alloy or the like.

Outwardly disposed, angular flanges 2

and 3 respectively are formed upon the side and bottom edges of each plate and provided with spaced openings 4, by means of which the side and bottom timbers 5 and 6 60 respectively are connected to the flanges as by the bolts 7.

As illustrated at 8 in Figs. 1 and 3, each of the flanges 2 and 3 terminates in an angular cut-out portion at the lower corners 65 of the plate, and as best shown in Fig. 5, the flanges 2 and 3 are not connected at their intersections, a narrow slot 9 separating the flanges at this point.

For the purpose of strengthening the end 70 plates, the intersection, vertical and horizontal ribs 10 and 11 may be formed upon the outer face of each plate, terminating in the side and bottom flanges 2 and 3 respectively and the narrow upper flange 12. 75

Each of the side and bottom flanges is provided at its edge with the angular rib 13 adapted to enter corresponding grooves 14 in the side and bottom timbers of the 80 tank. If desired, asphalt or other packing material may be used for sealing the joints between the flanges and the timbers.

In assembling the tank, the side and bottom timbers are preferably grooved upon their engaging faces as shown at 15, tongues 85 16 engaging the grooves of adjacent timbers to hold the same in alignment and sealing the joints between the timbers which are tied together as by the tie bolts 17.

The timbers are connected to the flanges 90 2 and 3 of the end plates by the bolts 7 and a wooden wedge 18 is driven into each corner of the end plate at the intersection of the corner timbers, thus closing the joints between the corners of the end plates and 95 the timbers.

With this construction a liquid tight tank is provided, the slots 9 at the intersection of the side and bottom flanges upon the end plates permitting for expansion and contraction of the metal end plates, without loosening the joints of the timbers, while the wooden wedge 18 at each corner of the end plate forms a liquid tight seal at this point, permitting for expansions and contraction 105 of the end plates.

Since the ends of the tank are formed of acid resisting metal, tightly sealed as above described and of sufficient strength to prevent breaking or destruction of the same by 110 the endwise ramming of bars or sheets being pickled in the tanks, it will be seen that

the difficulties common in acid tanks now in general use are overcome.

I claim:

1. An acid tank including metal end walls provided with angular flanges at their side and bottom edges, the flanges being separated from each other at their ends, and wooden side and bottom walls connected to said flanges.
- 10 2. An acid tank including metal end walls provided with angular flanges at their side and bottom edges, said flanges having angular ribs at their edge portions, and

wooden side and bottom walls connected to said flanges and having grooves to receive 15 said ribs.

3. An acid tank including metal end walls provided with angular flanges at their side and bottom edges, the corners of the metal end walls being cut out, wooden side and bottom walls connected to said flanges, and wooden wedges located between the cut-out corners and the adjacent wooden walls. 20

In testimony that I claim the above, I have hereunto subscribed my name.

ROBERT C. HOPKINS.
